UNITED STATES PATENT OFFICE.

DAVID R. BONE, OF OGLESBY, TEXAS.

HOLLOW-TILE BUILDING BLOCK.

Application filed December 30, 1922. Serial No. 610,048.

To all whom it may concern:

Be it known that I, DAVID R. BONE, a citizen of the United States, residing at Oglesby, in the county of Coryell and State 5 of Texas, have invented new and useful Improvements in Hollow-Tile Building Blocks, of which the following is a specification.

This invention relates to hollow tile building blocks, also to a wall-assembly constructed of such blocks.

Where a wall assembly is of such construction that a mortar-joint extends straight through the assembly, the moisture 15 can penetrate from the exterior to the interior with comparatively little resistance, as compared with a wall assembly in which the mortar-joints are broken by vertical portions which imposes the resistance of the 20 force of gravity against the force of capillary attraction, and at the same time lengthens the mortar-joints, thus imposing additional resistance to the entrance of moisture to the interior. Therefore, one object of 25 this invention is to provide a building block of such construction that it will impose the above mentioned resistances when assembled with others of its kind and others of an ordinary or cubical form. And another 30 object, in a block of this character, is to insure an interlocking of all the blocks of the wall-assembly. A further object is to provide a cruciform block of such character that it may be assembled and united 35 with four cubical blocks so as to form a block or wall-section having a tongue at one side and a groove at the other side, so any number of such wall-sections can be united in tongued and grooved and interlocked relation for forming a wall, and which can be 40 properly terminated or finished by the addition of separate units such as those of which it is composed, or any desired or required fractional part of such units.

45 In the accompanying drawings, in which similar reference characters correspond to similar parts in the several views:

Fig. 1 is an elevation of one of the main or cruciform blocks or units: Fig. 2 is an 50 elevation of one of the cubical blocks or units such as I prefer to use to form part of the exterior side of the wall or wall-section: Fig. 3 is an elevation of one of the cubical blocks or sections such as I prefer to use to form part of the interior side 55 of the wall or wall-section: Fig. 4 is an ele-

vation of an assembly of one of the main blocks and four of the lesser or cubical blocks, these being substantially in the arrangement for forming one of the above mentioned wall-sections, but being slightly spaced from one another to more clearly define the limits of each unit: And Fig. 5 is an elevation, in perspective, of a wall-assembly having at one end two cruciform 60 blocks and six cubical blocks, showing how the units of Figs. 1, 2 and 3 (one each) are assembled on top of one of the wall-sections of Fig. 4.

In the several views, the several units are 70 respectively represented by the numerals 1, 2 and 3. The cruciform blocks are each formed with a middle or mid-wall portion which is the same height as the lateral extent of the block, and consists of three cells 75 which are approximately equal in size and shape. The lateral extent of this upright portion is substantially one-third of the vertical extent. It is formed with opposed lateral extensions 1^a which are cubical, and each of these extensions consists of one cell substantially the same as those of the middle upright part; so the lateral reach of each part 1^a is equal to the lateral extent of said upright middle part. The centers of these 80 lateral extensions are in the same horizontal plane with the partition that separates the two upper cells of the middle upright part; so the latter extends one-half of its 85 length below these extensions, and one-sixth of its length above them, the other one-third of its length being between them. The lateral and vertical extent of each part 1^a is 90 approximately the same as that of each of the units 2 and 3, allowing a slight difference to compensate for the mortar-joints 95 between these extensions and units; thereby providing for the assembling to form the section and wall-assembly shown in Figs. 4 and 5.

100 Figures 4 and 5 show clearly how the mortar joints are offset or broken at each one-third the distance through the wall, and how the units interlock through a vertical section of the wall. Fig. 5 also shows how the units 105 are interlocked longitudinally, and how, in spite of such interlocking of the units, a plane wall-end or finish is obtained by providing the units in single lengths and double lengths: However, the longitudinal interlocking may be obtained in other ways and 110 by other assemblies of the blocks or units;

for instance, by assembling them in groups of five, as shown in Fig. 4, then uniting the units by means of cement or mortar, thus forming the above defined wall-sections each 5 having a tongue and a groove at its lower and upper ends. It is obvious that these wall sections can be assembled to form a wall having tongue-and-groove joints and broken vertical joints, by interlapping these 10 wall-sections so that each course breaks the joints of the courses above and below it.

As this cruciform building block is capable of numerous advantageous applications, as partly shown in the foregoing, it is 15 not intended to limit my protection by conforming to any particular one of such applications; but what I claim as my invention is:

1. The cruciform building block of which 20 the upright middle part is substantially three times as high as its lateral width and is formed with lateral extensions which are horizontally opposite to one another and are substantially equal in height and lateral 25 extent to the lateral width of the said middle part, said middle part extending above the lateral extensions about one-half the distance of its lateral extent, said middle part extending below said lateral extensions 30 about one and one-half times the distance of its lateral extent, substantially as shown, for the purpose specified.

2. The cruciform building block which 35 includes an upright middle part formed of three substantially equal cells separated by laterally or horizontally disposed partitions the upper one of which is substantially twice

the distance from the bottom as from the top, this central upright part being formed with two horizontally opposite extensions 40 each consisting of one cell substantially equal to the cells of said upright part, the centers of these lateral extensions being substantially in the same level with the said upper partition, the upright part extending above the lateral extensions a distance of 45 about one-half the height of each lateral extension, the upright part extending below the lateral extensions a distance of about one and one-half times the height of each lateral extension, the lateral extent of the upright part and of each lateral extension being substantially equal to the height of the latter.

3. The combination of a cruciform building block having its lateral extensions substantially equal in height and lateral extent to the lateral extent of the middle upright part, said lateral extensions being nearer the upper end and farther from the lower end 60 of the middle upright part than the lateral extent of the latter, the lateral extent of said middle upright being substantially equal to the lateral extent and to the height of each lateral extension; and four rectangular blocks in the angular spaces above and 65 below the lateral extensions, thus forming a wall-section having a tongue at one side and a groove at its opposite side, substantially as shown, for the purposes specified. 70

In testimony whereof I have affixed my signature.

DAVID R. BONE.
